UNITED STATES PATENT OFFICE.

ALCUIN E. KINTNER, OF PAINESVILLE, OHIO, ASSIGNOR, BY MESNE ASSIGNMENTS,
TO THE NEFF COMPANY, OF CLEVELAND, OHIO, A CORPORATION.

DOOR LATCH.

Application filed October 6, 1921. Serial No. 505,911.

To all whom it may concern:

Be it known that I, ALCUIN E. KINTNER, a citizen of the United States, residing at Painesville, in the county of Lake and State 5 of Ohio, have invented certain new and useful Improvements in Door Latches, of which the following is a specification.

This invention relates to a door latch, more particularly to a combined latch and lock capable of application to a door, whereby it may be held closed and also locked, when desired.

One object of the invention is to provide a latch of simple construction capable 15 of being easily applied to a door.

Another object of the invention is to provide a latch of novel construction capable of application to either a right-hand or left-hand swinging door.

20 Another object of the invention is to provide an improved combined latch and lock of relatively simple construction and capable of ready application to doors of various types.

25 Another object of the invention is to provide a reversible door latch and to combine therewith a relatively simple locking member correlated to operate in either position in which the latch is placed.

30 A further object of the invention is to provide an improved combined latch and lock capable of application to a sliding door.

A further object of the invention is to 35 provide an improved latch so constructed that it may be applied to a right-hand swinging door, a left-hand swinging door or a sliding door, as desired.

Other objects of the invention will be 40 apparent to those skilled in the art to which my invention relates from the following description taken in connection with the accompanying drawings.

In the drawings, Fig. 1 is a fragmentary view of a door frame and door to which is 45 applied a door latch embodying my invention.

Fig. 2 is a section on the line 2—2 of Fig. 1.

Fig. 3 is a section on the line 3—3 of 50 Fig. 1.

Fig. 4 is a perspective view of the latch.

Fig. 5 is a perspective view of the keeper.

Fig. 6 is a perspective view of the locking member, detached.

55 Fig. 7 is a sectional view corresponding

to Fig. 3, but showing the keeper applied for engagement by a latch on a right-hand swinging door and the locking member in normal position.

Fig. 8 is a fragmentary view, partly in 60 section, showing a modified form of construction for use in latching and locking a sliding door.

Fig. 9 is a section on the line 9—9 of Fig. 8, looking toward the left. 65

Figs. 10 and 11 are sectional views on the line 9—9 of Fig. 8, looking toward the right; the former figure showing the locking member in normal position and the latter figure showing the locking member in 70 operated position and locked by a suitable lock.

Referring to the drawings, 1 indicates a door frame. 2 indicates a door hinged along its left-hand edge to the frame 1 by suitable hinges 3, only one being shown. 4 indicates a latch pivoted at its inner end on a pivot pin 5, whereby its outer or free end may be engaged with or disengaged from a keeper, indicated as an entirety at 6. The 75 pivot pin 5 may be secured or mounted upon the door 2 in any suitable manner, but by preference the pin 5 extends through an opening 7 in the door 2 and is secured therein by a nut 8 screw-threaded on its 80 inner end. In order that the latch 4 may be adapted for a right-hand or left-hand swinging door, I prefer to form it from a substantially U-shaped member 4' and to dispose the legs 4^a of the U upon opposite 85 sides of the door 2 and to pivot both ends of the member on the pivot pin 5. At a point centrally of the base 4^b of the U, the metal is bent outwardly and then back on itself, as shown at 4^c, to form a projection 90 4^{c'} which engages and disengages the keeper 6 in the manner to be hereinafter set forth.

Intermediate their ends, the legs 4^a of the U-member are preferably bent laterally or outwardly to form handles by means of 100 which the latch may be elevated at either side of the door.

7 indicates a sheathing preferably comprising a U-shaped member formed from sheet metal, and adapted to fit the opposite 105 sides of the door 2 and guard it against wear or damage due to the operation of the latch 4. Near their inner ends, the side plates 7^a, 7^b, of the sheathing 7 are formed with aligned openings 7^b, which serve as suit 110

able bearings for the pivot pin 5. The end wall of the member 7 is preferably cut away, as shown at 7^c, to form shoulders 7^d, which limit the raising and lowering of the latch 4. When the sheathing 7 is provided, the latch 4 is made of proper size to fit in the cut-away 7^c and engage the shoulders 7^d. The sheathing may be secured to the door 2 by suitable screws 8.

10 The keeper 6 preferably comprises a plate 6' formed with notches 6^a, 6^{a'}, on its upper and lower edges respectively, and provided with an integral extension or arm 6^b, the upper and lower edges 6^c, 6^{c'}, of which are inclined toward each other, whereby either may serve as a guide for the latch 4 to guide it to the adjacent notch accordingly as the keeper 6 is positioned on the door frame 1. 9 indicates a flange extending 20 along each inclined edge 6^c, 6^{c'}, to form a relatively wide guide surface for the latch 4 to ride on when the door is closed. The flanges 9 are preferably formed integrally with the extension 6^b. By preference (as 25 shown in Fig. 5), the notches 6^a, 6^{a'}, and guides 6^c, 6^{c'}, are disposed equal distances from a longitudinal line extending centrally through the extension 6^b. The keeper is shown in Figs. 1, 2 and 3 as applied to a 30 left-hand swinging door; when so disposed, the guide 6^c and notch 6^a are arranged for engagement by the latch 4. When the door is a right-hand swinging door, the plate 6' is applied in the same manner, but it is 35 reversed so that the guide 6^{c'} and notch 6^{a'} are arranged on the upper side of the plate for engagement by the latch 4, as shown in Fig. 7.

40 10 indicates an opening formed in the free end of the extension 6^b, preferably in line with the central, longitudinal axis thereof. The purpose of the opening 10 will be later set forth.

45 11 indicates a locking member adapted to engage the latch 4 and lock it in the notch 6^a, or 6^{a'}, as the case may be. The locking member 11 is common to both notches 6^a, 6^{a'}, whereby it may operate as a lock in the event the keeper 6 is applied to either a 50 right-hand or a left-hand door. The locking member 11 preferably comprises a body portion 12, pivoted at 13 to one face—preferably the outer face—of the plate 6' at a point midway between the bottom walls 55 of the notches 6^a, 6^{a'}, and a pair of diverging arms 14, 15, provided with shoulders 14^a, 15^a, respectively, at their free ends. The arms 14, 15, are of equal length, whereby the shoulder of one or the other may 60 overlie the adjacent notch accordingly as the keeper is applied to a right-hand or a left-hand swinging door. In Fig. 3, the locking member 11 is shown in dotted lines in its normal position, (at which time the latch 4 may engage and disengage the notch

6^a); but by swinging the locking member to the position shown in full lines, the shoulder 14^a of the arm 14 will overlie the notch 6^a and thereby lock the latch 4 therein. When in this latter position, one of the 70 openings 16 in the arm 15 is adapted to register with the opening 10 in the extension 6^b, to permit the application of a lock element, such as a pad-lock 17. When the keeper 6 is applied to a right-hand door, 75 it will be understood that the locking member 11 will in normal position be disposed as shown in Fig. 7 and when it is desired to lock the latch 4, it will be swung on the pivot 13 until the shoulder 15^a of the arm 15 will 80 overlie the notch 6^{a'}. When so arranged, the arm 14 and extension may be secured together by a pad-lock 17 in the manner already described in connection with the arm 15. 85

In Figs. 8, 9, 10 and 11, I have shown a slightly modified form of construction particularly adapted for use for latching and locking a sliding door. In these views, 1^x indicates the door frame and 2^x indicates the 90 door slidable longitudinally in guides 2^{rx}, of any desired construction. In this form of construction all the elements of the combined latch and lock are similar in construction to like elements referred to in connection with the construction shown in Figs. 1 to 7, inclusive, except the latch, indicated at 4^x. As shown in Fig. 8, the extension 4^x of the latch 4^x is formed on its lower edge with a notch 17, the walls of which are adapted to engage and disengage the bottom wall of one of the notches 6^{ax}, 6^{ax}, of the keeper 6^x. To permit the latch 4^x to automatically engage the keeper as the door 2^x slides to closed position, the free end of the extension 4^x is beveled, as shown at 18. In operation, the beveled edge 18 rides on the bottom wall of the notch 6^{ax} to elevate the latch 4^x, in order that the notch 17 may 105 engage the keeper. The keeper 6^x may be applied to the door frame 1^x so that either notch 6^{ax}, 6^{ax}, may be used for latching the door 2^x. The latch 4^x may be locked in latched position by the shoulder 14^{ax} provided on the arm 14^x of a locking member 11^x, which is similar in construction and operation to the locking member 11 correlated with the latch shown in Figs. 1 to 7, inclusive. 110

While the form of construction shown in Figs. 1 to 7, inclusive, is suitable for right-hand and left-hand swinging doors only, the form of construction shown in Figs. 8 to 11, inclusive, may be used on either a right-hand or a left-hand swinging door, if desired, as well as on a sliding door. When the latter form of construction is applied to a swinging door, the latch 4^x will operate similar to the latch 4, since that portion of the extension 4^x disposed between outer side 120

wall of the notch 17 and the bevel edge 18 is adapted to engage the adjacent flange 9^x of the keeper 6^x and guide the latch extension 4^x into the adjacent notch 6^{ax} and thus 5 permit the walls of the notch 17 to engage the bottom wall of the keeper notch, as shown in Fig. 8.

It will be understood that my disclosures and the description herein are purely illustrative and are not intended to be in any sense limiting, as widely differing embodiments and applications of my invention will suggest themselves to those skilled in the art without departing from the spirit and 10 scope thereof.

What I claim is:

1. In a door latch, the combination of a latch adapted to be pivoted to a door, a keeper comprising a plate having a notch in 20 its upper portion arranged to receive said latch, and a locking member movably mounted on said keeper and having arms, one arranged to overlie said latch when it is in said notch to lock it therein and the 25 other arranged to be secured to said keeper to maintain the first mentioned arm in locking position.

2. In a door latch, the combination of a latch adapted to be pivoted to a door, a keeper comprising a plate having notches in 30 its upper and lower portions either arranged to receive the latch accordingly as the latch and keeper are applied for a right-hand or left-hand door, and a locking member movably mounted on said keeper having arms 35 each operative to overlie the adjacent notch and lock the latch therein, and the other arm arranged to be secured to said keeper to maintain the operative arm in locking 40 position.

3. In a door latch, the combination of a latch comprising a U-shaped member the legs of which are disposed upon and pivoted to the opposite sides of the door and an 45 extension arranged intermediate its ends, and a keeper adapted to be fixed to a door frame and formed with aligned notches in its upper and lower edges and provided with an arm having upper and lower edges inclined toward each other, whereby one of 50 said edges serves to guide the latch to the adjacent notch accordingly as the keeper is applied to the door frame.

4. In a door latch, the combination of a 55 latch having a beveled free end and a notch formed in its lower edge, and a keeper having a notch formed in its upper edge and provided with an extension having an inclined upper edge for guiding the latch to the adjacent notch when the latch is applied 60 to a swinging door.

5. In a door latch, the combination of a latch having a beveled free end and a notch formed in its lower edge, a keeper having 65 a notch formed in its upper edge and pro-

vided with an extension having an inclined upper edge for guiding the latch to the adjacent notch when the latch is applied to a swinging door, and a locking member pivoted to said keeper and arranged to be 70 moved into position to overlie the notch in said keeper to lock the latch therein.

6. In a door latch, the combination of a latch having a beveled free end and a notch formed in its lower edge, a keeper having 75 a notch formed in its upper edge and provided with an extension having an inclined upper edge for guiding the latch to the notch formed in the keeper when the latch is applied to a swinging door, and a locking 80 member having a pair of arms, said member being pivoted to said keeper, whereby it may be moved to dispose one arm into position to prevent unlatching of the latch and the other arm in alignment with said extension, whereby it may be locked thereto.

7. In a combined latch and lock, the combination of a latch adapted to be pivoted to a door, a keeper comprising a plate having a notch and an arm having an inclined 90 edge for guiding the latch to said notch, and a locking member pivoted to said keeper and arranged to be moved into position to overlie the notch in said keeper to lock 95 the latch therein.

8. In a combined latch and lock, the combination of a latch adapted to be pivoted to a door, a keeper comprising a plate having a notch and an arm having an inclined 100 edge for guiding the latch to said notch, and a locking member having a pair of arms, said member being pivoted to said keeper, whereby it may be moved to dispose one arm in position to prevent unlatching of the latch and the other arm in alignment with 105 said first mentioned arm, whereby it may be locked thereto.

9. In a combined latch and lock, the combination of a latch adapted to be pivoted to a door, a keeper comprising a plate formed with notches in its upper and lower edges and provided with an extension having inclined upper and lower edges, whereby said plate may be applied to a door frame for engagement by the latch when applied to either a right-hand or left-hand swinging door, and a locking member movably mounted on said keeper and common to both of 110 said notches, whereby it may operate to lock the latch in either position of said keeper.

10. In a combined latch and lock, the combination of a latch adapted to be pivoted to a door, a keeper comprising a plate formed with notches in its upper and lower edges and provided with an extension having inclined upper and lower edges, whereby said plate may be fixed to a door frame for engagement by the latch when applied 115 to either a right-hand or left-hand swing-

ing door, and a locking member pivotally mounted on said keeper and common to both of said notches, whereby it may operate to lock the latch in either position of said keeper.

11. In a combined latch and lock, the combination of a latch adapted to be pivoted to a door, a keeper comprising a plate formed with notches in its upper and lower edges and provided with an extension having inclined upper and lower edges, where-
by said plate may be applied to a door frame for engagement by the latch when applied to either a right-hand or left-hand swinging door, and a locking member movably mounted on said keeper and provided with a pair of arms each adapted to overlie one of said notches in said keeper, where-
of said member may operate to lock the latch in either position of said keeper.

12. In a combined latch and lock, the combination of a latch adapted to be pivoted to a door, a keeper comprising a plate formed with notches in its upper and lower edges and provided with an extension having inclined upper and lower edges, where-
by said plate may be fixed to a door frame for engagement by the latch when applied to either a right-hand or left-hand swinging door, and a locking member movably mounted on said keeper and provided with a pair of arms each adapted to overlie one of said notches in said keeper, where-
of said member may operate to lock the latch in either position of said keeper.

13. In a combined latch and lock, the combination of a latch adapted to be pivoted to a door and formed with a beveled free end and a notch in its lower edge, a keeper comprising a plate formed with notches in its upper and lower edges and provided with an extension having upper and lower inclined edges, and a locking member common to said notches and mov-
able on said keeper to a position to prevent unlatching of said latch from either notch formed in said keeper accordingly as it is applied for a right-hand or left-hand swinging door or a sliding door.

In testimony whereof I have hereunto affixed my signature.

ALCUIN E. KINTNER.
